Re: Table VIII

BY Fisher & Moser ATTYS.

UNITED STATES PATENT OFFICE.

CHARLES A. JOHNSON AND ALFRED L. MILLS, OF NORTH RIDGEVILLE, OHIO.

CATCH-BASIN COVER.

No. 918,860.

Specification of Letters Patent.

Patented April 20, 1909.

Application filed January 20, 1909. Serial No. 473,344.

To all whom it may concern:

Be it known that we, CHARLES A. JOHNSON and ALFRED L. MILLS, citizens of the United States, residing at North Ridgeville, 5 in the county of Lorain and State of Ohio, have invented certain new and useful Improvements in Catch-Basin Covers, of which the following is a specification.

Our invention relates to catch basin covers, and the invention consists in the construction and combination of parts, substantially as shown and described and particularly pointed out in the claims.

In the accompanying drawings, Figure 15 1 is a cross sectional plan of the basin mechanism on a line corresponding to $z-z$, Fig. 2. Fig. 2 is a side elevation of said mechanism, and Fig. 3 is a vertical cross section thereof on line $w-w$, Fig. 4. Fig. 4 is a 20 plan view of the front portion of the said mechanism, and a cross section of the rear portion corresponding to line $y-y$, Fig. 8. Fig. 5 is an end elevation of a portion 25 thereof on a line corresponding substantially to $6-6$, Fig. 5. Fig. 6 is a sectional elevation of a part of the curb member on line $6-6$, Fig. 5. Fig. 7 is a perspective view of one of the fastening bolts and heads for the said curb section, and Fig. 8 is a 30 cross sectional elevation on line $x-x$, Fig. 4.

The parts as thus shown and described make up a complete catch basin mechanism or cover for the basin adapted to both the basin and the curbing of a street more or less after the manner of such mechanism usually. To these ends the cover proper for the basin, indicated by C, has the usual flat base or flange portion c, adapted to lie flat upon the top of the catch basin, and a 35 rectangular or box shaped wall 2 constructed to support the added parts and which go to make up a complete structure, substantially as shown. To these ends the front portion of said rectangular part or box 40 is provided with lugs 3, or their equivalent, on the inside adapted to support the grate G which rests thereon and which is locked in place by bolt a having an underlying lip b. The top of the grate is flush with the top 45 of the wall 2 of said cover, as usual, and presumably flush with the paved surface of the street.

D represents the curb member, which is a 50 separate part entirely and adapted to fit within the angles of the box portion 2 of the cover and to be slidably mounted therein to

accommodate the same to the depth or elevation of the curbing as the same may be found here and there in different streets. The adjustment herein provided for is vertical, and the fastenings for said curb member are wholly on the inside. To these ends the said curb member has plain flat surfaced ends and rear corresponding to the shape and size of box 2 and fitting slidably but 55 snugly therein so as to be held firmly between the walls thereof and thus contribute to its own support. The fastening means, however, are necessary to fix the said member at any given elevation, and to these ends 60 I construct the box 2 with vertical grooves or channels 4 undercut along their edges in dovetail fashion, open along the inside of the box and covered over their outside and adapted to receive the oppositely or re- 65 versely dovetailed ribs 5 on the curb member and the heads 6 of the fastening bolts 7. Curb member D is provided with recesses 9 in its ribs 5 and holes d in said recesses adapted to receive the said bolts, which necessarily 70 are inserted before the said member is put in place, and the heads of said bolts are dove- 75 tailed or beveled with a decided flare to correspond with the ribs 5 and to enter the channels 4 in the said box with said ribs and 80 frictionally lock therein, thus holding the 85 said member D fast. Said ribs have recesses or notches 9 adapted to receive the said heads. Then as said member is introduced and set at the desired level the nuts 8 are 90 tightened and the beveled heads 6 engage the beveled surfaces of said channels and lock the said part firmly in place. The rear chan- 95 nel or groove 4 is like the corresponding grooves at the ends, as is also the bolt 7 and its head 6, but no beveled rib like 5 is needed at the rear. A pair of vertically disposed 100 overflow guards, shown as plain bars 12, have eyes or holes in their upper ends and are secured therethrough by bolts 14 upon the inside of the top cross portion of the said curb member. Otherwise the said guards 12 are slidably mounted in keepers 15 cast in the rear edge of the grate, and two or more such bars or their equivalent may be used. 105

The grate G is recessed or cut out in its rear corners to engage under the lugs 17 on the box 2, which enter into said recesses flush with the top of the grate, so that the grate is first inserted between these lugs and 110 the supporting lugs 3 beneath and then a single fastening bolt a and catch b on the

same at the center and front of the grate serves to hold the grate securely down in place.

Practically the device is made up of three pieces, the cover C, the curb member D and the grate G, bars 12 being guards adapted to detain such objects that might impede or obstruct the down passage into the basin.

By constructing the curb member with the dovetailed guide ribs and forming the corresponding channels 4 in the box 2 we obtain not only a rigid construction of the parts but also a blind connection so far as the outside is concerned, there being no holes or bolts or the like exposed outside of the structure to make the connection and adjustment of said curb member. Again, the ribs and channels combined alone serve to keep the curb member in perfect alinement and to prevent displacement forward or backward under any possible strain short of breakage, and hence the strain does not come on bolts 7 but on said ribs, and the bolts serve to retain the curb member in any adjusted position. For this reason, also, the rear of said member does not require a rib, but the bevel headed bolt alone is sufficient. Shoulders 20 on the sides of the curb member are adapted to rest down on the edge of box 2 and prevent it from sliding down below or lower than said shoulders.

It will be noticed that box 2 has swells or enlargements 22 within which the channels 4 are formed, and there is a fairly close fit between the ribs 5 and said channels for the purposes above set forth.

The box 2 of the base C is open across its entire bottom so as to have a free and open discharge into the basin without possible obstruction.

The recesses 9 are near the bottom edge of the curb member so as to keep the bolts 6 always within the adjusting space, but shoulders 20 prevent the curb member from going too low to lock the bolts in the cover, and lugs 17 from shoulders at the front against which the curb member may come if the dovetailed connections are loose enough to allow this to occur. The said curb member 50 itself is box shaped and wholly closed over

its top sides and rear, and open front and bottom.

What we claim is:

1. In catch basins, a base having a rectangular box shaped top portion with parallel walls and open across its entire bottom, said walls being provided with flaring channels at its sides and rear extending the full depth thereof, in combination with a curb member having dovetailed ribs conforming 55 to said channels and slideable therein, and bolts having heads conforming in shape to said ribs and adapted to engage and lock against said flaring channels and fix said curb member in place.

2. In catch basins, a base having a box shaped vertical portion open across its top and bottom and provided with dovetailed channels inside at its sides and rear, in combination with a curb member having dove-tailed ribs engaged in said channels and provided each with a recess and a bolt hole in said recess, and bolts engaged in said holes having heads seated in said recesses and constructed to frictionally engage said dove-tailed channels and fix said curb member at any desired elevation.

3. In catch basins, a cover having a rectangular vertical wall provided with dove-tailed channels inside at its rear and lugs inside at its front, in combination with a grate supported on said lugs and having keepers in its rear edge, a curb member adjustably engaged in said channels and guard pieces fixed at one end in the front and top of said curb member and slidably mounted in said keepers.

4. In catch basins, a cover having vertical channels in its sides and rear, in combination with a curb member having ribs engaged in 90 said channels respectively, and bolts through said curb member adapted to lock the same in adjusted position in said cover.

In testimony whereof we affix our signatures in presence of two witnesses.

CHARLES A. JOHNSON.
ALFRED L. MILLS.
